SEAL

Hans F. Stoffel, Scarsdale, N. Y.

Application April 12, 1949, Serial No. 87,038

5 Claims. (Cl. 292—322)

1

The invention relates to seals and more particularly to a tamperproof self-locking tag seal adapted to be fixed to a tie cord or other binding means, the seal being constructed to be closed manually without the use of special tools.

The main object of the invention is to provide a tamperproof self-locking seal having locking means bent into an interlocked position after the seal is closed.

Another object is to incorporate additional locking means adapted to cause a snapping action after the tamperproof locking means are interlocked so that the person applying the seal has the assurance that the seal is positively locked.

A further object is to weaken the seal in such a way that if an attempt is made to reopen the seal, part of it is torn and therefore becomes unfit for reuse.

The invention also aims at a simple construction of a seal of the above type that can be made economically and lends itself to mass production methods.

Other objects and advantages of this invention will be apparent from the following description considered in connection with the accompanying drawing submitted for the purpose of illustration and not to define the scope of the invention, reference being had for that purpose to the subjoined claims. In the drawing, wherein similar reference characters refer to similar parts throughout the several views:

Fig. 1 is a rear view of the open seal as manufactured;

Fig. 2, a section taken on line 2—2 of Fig. 1;

Fig. 3, a section taken on line 3—3 of Fig. 2;

Fig. 4, a rear view showing the tag in the closed position affixed to a cord;

Fig. 5, a section taken on line 5—5 of Fig. 4, and

Fig. 6, a section taken on line 6—6 of Fig. 4.

Before explaining the present invention in detail, it is to be understood that the invention is not limited in its application to the details of construction and arrangement of elements illustrated in the accompanying drawing, since the invention is capable of other embodiments and of being practised or carried out in various ways. Also it is to be understood that the phraseology or terminology employed herein is for the purpose of description and not limitation.

In the embodiment shown, the seal is stamped of a single piece of sheet metal and comprises two casing sections 10 and 11 bent toward each other into opposed relation, the bending line being at 12, so that when the two sections are bent to-

2

gether into a closed position they form a box-like structure to receive and inaccessibly enclose the end of a tie cord 13 or other binding element. Casing 10 has its edges bent up to form side walls 14 and end walls 15, the latter being folded over inwardly parallel with the bottom wall of casing 10 to serve as a locking plate 16 for which purpose it is provided with a slot 17 positioned to receive tongue 18 of casing section or flap 11 whose lateral edges are also bent over to form side walls 19 fitting inside walls 14 when the seal is closed. Tongue 18 is perpendicular to the bottom wall of flap 11, or on an arc struck from point 12 as viewed in Fig. 2 to pass through slot 17 when flap 11 is swung about point 12 into a closed position. A shear cut or slot 20 in tongue 18 produces a catch 21. The purpose and function of this catch is to prevent the retraction of tongue 18 after it has entered slot 17, the curvature 22 of wall 15 serving to deflect the outer extremity of tongue 18 so that catch 21 is bent out of the plane of the tongue after it has passed through the slot. The bending takes place on line 23 which is at the weakest section of the tongue, but in addition, the tongue may also be weakened on line 23 by impression. Thus the outer portion of the tongue and catch 21, bordered by the outer edge, slot 20, and lines 23, are a rigid surface adapted to turn out of the plane of tongue 18 about an axis extending through lines 23. This surface may be further strengthened by a rib or other reinforcement. Curvature 22 and the tip of tongue 18 must be in the proper relation so that the outer portion of the tongue is deflected after catch 21 has passed through slot 17. Thus deflection of catch 21 to lock tongue 18 in slot 17 is effected only by folding flap 11 against portion 10 a short distance beyond the point where the tip of catch 21 passes slot 17. To assure the performance of this operation a snap 24 in the form of tooth means is provided at one side near the base of the tongue in a position where it catches in slot 17 after the abutting edge of catch 21 has passed a short distance beyond slot 17. It will be observed by inspection of Fig. 3, that the toothed edge of snap 24 is farther away from the tip of the tongue than catch 21, and it extends farther to the left than slot 17 so that in the closing operation to allow snap 24 to pass through the slot, flap 11 is sprung out of place laterally to spring back into position with a snapping sound after tooth or snap 24 has passed through the slot. Locking means are thus provided not only in the form of catch 21, but also by snap or tooth 24. To

prevent tampering with the seal after it is attached, I provide weakened lines at 25 so that when opening is attempted with a sharp tool inserted between end portions 26 and plate 16 a tear is produced on line 25.

The article described may be used as a seal or as a tag, where the face of the casing 10 and the back of flap 11 are suited to carry the desired indicia, preferably in printed form. To attach the manufactured article shown in Figs. 1 and 2 to a cord or other binding element 13, the latter is inserted between the open jaws of the seal to a place near or adjacent and parallel with fold 12, whereby the end or ends of the cords preferably extend a short distance outside of the seal. Then the two sections 10 and 11 are bent upon each other so that the cord becomes pinched between 10 and 11 as shown in Fig. 5. During this closing operation tongue 18 enters slot 17 whereby the tip of the tongue is deflected on cam surface 22 as soon as catch 21 has passed through the slot, the deflection occurring about lines 23 whereby the tip of catch 21 moves out of the plane of the tongue as shown in Fig. 6, to prevent subsequent retraction through slot 17. After the end of the short movement necessary to deflect the tip of tongue 18 tooth 24 snaps into a locking position as it passes past slot 17 so that the seal is now securely locked.

It is apparent that the novel seal may secure various types of binding elements such as cords, ribbons, or stranded wire, and any such element may be tied in a knot, and the knot encased within the casing or box formed by the seal.

Having thus described the invention, what is claimed as new and desired to be secured by Letters Patent, is:

1. A seal construction comprising two casing sections having a fold line about which they may be bent toward each other in opposed relation for closing said seal, whereby an element to be sealed may be received between said sections, one of said sections having an end wall disposed opposite the fold line and extending inwardly in the direction toward said fold line to thereby form a plate approximately parallel with and spaced from the face of said one section, said plate being provided with a slot, the other section having a tongue opposite said fold line extending in a direction to cooperate with the wall defining said slot and to enter said slot when said two sections are folded together, a catch on said tongue adapted to be bent out of the plane of said tongue, the face of said one section being provided with a curved portion arranged to engage the tip of said tongue whereby said catch is bent out of the plane of said tongue

after it has passed through said slot in closed position of said seal, said catch and said tip of said tongue remaining permanently in one plane in said closed position of said seal, and tooth means projecting laterally from said tongue and forming snap means in cooperation with the adjacent end of said slot, said tooth means extending laterally beyond said adjacent end of said slot and being passable therethrough only by a temporary distortion of said two sections with respect to each other, whereby, upon folding of said two sections together, an audible snapping sound is emitted.

2. The construction as claimed in claim 1, wherein said tooth means is arranged to pass through said slot only after said catch is projected through the latter.

3. The construction as claimed in claim 2, including longitudinal weakened lines in said other section near the base of said tongue to render the seal unfit for re-use after tampering.

4. The combination, in a seal having two sections foldable upon each other into a locking position, of a tongue provided with a catch forming part on one of said sections, with a snap tooth positioned laterally and remote from said catch on said tongue, the other section being provided with a slot for receiving said catch and said snap tooth successively, said snap tooth being located on said tongue so as to project laterally beyond one end wall defining said slot for engaging behind said end wall, whereby during movement of said sections in said locking position said sections are temporarily laterally distorted with respect to each other and cause an audible snapping sound after said catch has passed said slot and is locked therein and upon subsequent passage of said snap tooth through said slot.

5. The combination according to claim 4, wherein said one section is provided with aligned weakened lines extending from said catch cross-wise to said tongue to form a bending line for said catch and further provided with a weakened line extending angularly to said aligned weakened lines and positioned adjacent said snap tooth to prevent tampering and to render the seal unfit for reuse after tampering.
